A. F. BROWN,
METALLIC RAILWAY TIE,
APPLICATION FILED OCT. 20, 1914

1,127,350.

Patented Feb. 2, 1915.

UNITED STATES PATENT OFFICE.

AUGUSTUS FREEBORN BROWN, OF HAVRE DE GRACE, MARYLAND, ASSIGNOR TO
GORRELL STEEL SPIKE LOCK RAILROAD TIE CORPORATION, OF HAVRE DE
GRACE, MARYLAND, A CORPORATION OF MARYLAND.

METALLIC RAILWAY-TIE.

1,127,350.

Specification of Letters Patent. Patented Feb. 2, 1915.

Application filed October 20, 1914. Serial No. 867,844.

To all whom it may concern:

Be it known that I, AUGUSTUS F. BROWN, a citizen of the United States, residing at Havre de Grace, in the county of Harford and State of Maryland, have invented certain new and useful Improvements in Metallic Railway-Ties, of which the following is a specification.

My invention relates to a metallic railway-tie and rail fastening, and the invention consists, essentially, of a railway-tie, formed of similar sections of pressed steel or like metal, each of said sections having on the upper surfaces near the ends, suitable transverse flanges with the flanges of one piece adapted to match and coöperate with similar flanges of the companion section to form suitable seats for the rails, said sections being, also, integrally formed below the sides of each rail seat, with a pair of vertically-disposed spaced spike receiving openings, which are closed on all sides, except the top and bottom, each of the sections of the tie being fashioned with similar portions of said spike receiving openings, which portions match to form a complete opening, said spike receiving openings having opposed interior walls, a part of which is formed in each of the similar sections of the tie, and said walls being fashioned sinuous or with alternate projections and depressions whereby a serpentine channel is formed for the reception of the spikes which secure the rails to the tie.

My invention also consists of the parts, and the constructions, arrangements and combinations of parts which I will herein-after describe and claim.

In the accompanying drawing forming part of this specification and in which similar reference characters indicate like parts in the several views:—Figure 1 is a perspective view of a railway-tie embodying my invention, showing the rails thereon in dotted lines. Fig. 2 is an inner side elevation of one of the pressed sections of the tie detached. Fig. 3 is a top plan view of Fig. 1. Fig. 4 is a detail of a portion of a section of the tie showing a rail in dotted lines secured thereto. Fig. 5 is a modification to be referred to.

In the said drawing A represents a railway-tie formed entirely of metal and, preferably, of two similar sections, A'—A², of pressed steel or the like, each of said sec-

tions comprising a transverse bottom flange, 55 a of suitable width, and a flange, b which, when the tie is in position, extends perpendicularly to the flange a, and rises from the inner edge thereof and extends from end to end of the tie.

The two sections, A'—A², of the tie are similar in character and construction and they are adapted to be joined together in some appropriate manner. This may be done by providing one of the sections with a pin or post, 10, which extends transversely from its inner surface and is designed to enter and extend through a corresponding opening, 12, formed in the flange portion b of the other section, the projecting portion 70 of the pin or post being then headed down to unite the sections, or, if desired, the projecting portion of the pin or post may be threaded to receive a suitable nut, as in Fig. 5.

For the sake of lightness and at the same time to give added strength to the tie, the vertical flanges b of the sections, A'—A², thereof may be formed with openings, c, at the ends and intermediate portions, as is 20 well known in this art.

The upper portion of the vertical flange b of each section of the tie is widened transversely by forming the section with horizontal flanges, d, one near each end, which 25 flanges are designed to match and to extend for a suitable distance along the upper edge of the section whereby when the two sections of the tie are fitted together, the horizontal flanges, d, form seats and supports 30 e, for the usual railway rails, B.

At the sides of the rail seats, e, the vertical flanges, b, and horizontal flanges, d, of the sections of the tie are formed integrally or otherwise provided with vertically matching shoulders, f, which abut the inner and outer edges of the horizontal base flanges of the rails, B, and by which lateral spreading of the rails is prevented.

If desired, the central portions of the rail seats, e, may be formed with matching openings, g, and end recesses g', a portion of each of which is formed in each of the horizontal flanges, d, of the sections. A portion of the vertical flange of each section beneath 10 the seats as well as the portion of the base flange of the tie and which is formed by the flanges, a, may be provided with openings,

h, h', respectively, but this construction is optional and forms no essential part of my present invention.

A leading feature of the present invention is in forming the pressed steel sections of the tie in such manner that the sections co-operate to form vertical spike receiving openings, *c*', located at opposite sides of and vertically below each rail-seat, said spike receiving openings being closed on all sides except the top and bottom, and the vertical flanges of the sections being slightly flared transversely, as at 13, to enable the spike receiving openings to be satisfactorily formed in and between the relatively thin edgewise standing flanges, *b*, of the tie, a portion of each of said spike receiving openings being pressed in each of the sections and the matching portions of the spike receiving openings co-operating to form a complete box. Each of the spike receiving openings also comprises two opposite walls, *c*', Fig. 4, which are sinuous or made with alternate curved projections and depressions, a transverse portion of each of these walls being formed in each of the pressed steel sections, before mentioned.

Each of the spike-receiving openings forms a vertical spike-receiving recess of serpentine form into which the ordinary and substantially straight railway spike, *f*', is designed to be driven and to be distorted during the operation, as shown in Fig. 4, whereby the spike is made to substantially conform to the wavy outline of the walls, *c*', *c*', of the opening against which the spike is forced as it is driven into place. The sinuous walls of the opening, therefore, give a corresponding wavy form to the spike which greatly adds to the security with which the spike is held. These walls also have the function of again straightening the spike when the same is withdrawn.

When it is desired to adjust the rails transversely to take up or compensate for wear of the treads of the rails I employ suitable metal shims, *D*, which may be normally straight and which are placed in the opening against one of the sinuous walls thereof whereby upon driving the spike in place the shim is crowded against and into the curvatures of the wall, and is thereby so distorted as to make it conform substantially to the wavy surfaces thereof, as shown in Fig. 4; at the same time the spike which is confined between the shim and the opposite sinuous wall of the opening is distorted and made to conform substantially to the formation thereof and also to that of the distorted shim. The pressed steel sections may also be formed along their upper outer sides with a strengthening rib, 14, which extends substantially from end to end of the sections, as shown in Fig. 1. The described tie is light and yet strong;

it is comparatively inexpensive, and it will be found an excellent substitute for the ordinary wooden tie, as also for the metal and composite tie now used for similar purposes.

Having thus described my invention what I claim as new and desire to secure by Letters Patent is:

1. A metallic railway-tie formed of similar sections of pressed metal each having a vertical flange extending longitudinally thereof and being formed integrally with a part of a rail seat and a part of an interior spike-receiving opening, said sections co-operating to form complete seats, and said openings being disposed at opposite sides of each of said seats and each of said openings extending toward the base of the tie, and having opposed interior walls of sinuous form adapted to distort normally substantially straight spikes when the latter are forcibly driven into the opening when in engagement with said walls. 75

2. A metallic railway-tie formed of similar sections of pressed metal each fashioned with a horizontal flange and a flange at right-angles thereto and extending longitudinally along the same, and means for uniting the sections of the tie, said sections having their upper edges near the ends, 90 formed with transverse oppositely projecting matching flanges which constitute widened rail seats, said vertical flanges of the sections being formed on their inner surfaces at opposite sides of each rail seat 100 with matching portions of a spike-receiving opening, each of said openings having opposed sinuous walls adapted to distort a spike simultaneously with the driving of the same into an opening whereby the spike 105 is made to conform substantially to the wavy outline of said walls.

3. A metallic railway-tie formed of similar sections of pressed metal each having a vertical flange and having matched portions 110 at the top constituting a rail-seat, each section of the tie having matching portions in their inner surfaces adapted to form spike-receiving openings, said openings being vertically-disposed at opposite sides of each of the rail-seats and having opposed sinuous inner walls, a portion of each of which is formed in each of the pressed sections of the tie, said sinuous walls adapted to distort a spike forcibly driven into said openings whereby the spike is made to substantially conform to said walls. 115

4. A metallic railway-tie formed of similar sections of pressed metal each having a vertical flange and having matching portions at the top constituting a rail-seat, each section of the tie having matching portions in their inner surfaces adapted to form spike-receiving openings, said openings being vertically-disposed at opposite sides of the rail- 120 125 130

seats and having opposed sinuous inner walls, a portion of each of which is formed in each of the pressed sections of the tie, said sinuous walls adapted to distort a spike 5 forcibly driven into said openings whereby the spike is made to substantially conform to said walls, and a metal shim introduced between the spike and one of the sinuous walls of an opening and adapted to be distorted 10 by and in unison with the distortion of the spike.

5. A railway-tie formed of similar sections of pressed metal each having a flange standing on edge and the inner surface of 16 each flange near the ends being formed

with parts of a pair of spike receiving recesses, parts of each of said recesses matching to form a complete opening and certain of the walls in the corresponding inner surfaces of the flanges being sinuous and adapted to distort a spike driven forcibly into the opening in contact with said sinuous walls. 20

In testimony whereof I affix my signature in presence of two witnesses.

AUGUSTUS FREEBORN BROWN.
